Atty.

UNITED STATES PATENT OFFICE

HANS PETER HANSON, OF CHICAGO, ILLINOIS

HANDLE FOR FLOWERPOTS AND SAUCERS

Application filed May 31, 1928. Serial No. 281,737.

My invention relates to a handle for the combination of a flowerpot and a saucer.

The primary object of my device is a handle of very simple construction having means to attach the same to a saucer device adapted to catch and retain an excess of fluid, and having means loosely mounted on the said handle whereby a flowerpot with contents may be seated in said saucer and be demountably locked to the handle, and be held in combination by the tensional coaction of the bow member. I also have as an object a provision of parts whereby the same can be dismounted and shipped in economical arrangement. Other objects will appear to those familiar with the art.

This application is based and is an improvement upon my former application Serial No. 184,544, filed April 18th, 1927.

An illustrative embodiment of my invention is shown in the accompanying drawing in which

Fig. 1 is an elevation, showing the parts of the device tensionally locked together.

Fig. 2 is an elevation, showing the several parts of the device before locking the pot.

Fig. 3 is an elevation, with a section of the pot and saucer cut away showing the tensional activity of the combination.

Fig. 4 is a broken section of saucer with a broken section of the handle in the position of the primary insertion of the handle in connection with the saucer.

Fig. 5 is an illustration of the saucer with a broken section of the handle in upright position.

Fig. 6 is broken section of the saucer, showing the hole and slots described in the specification.

As illustrated the combination consists of a flowerpot A, a saucer B, and a handle combination 10. The flowerpot A is any ordinary type of flowerpot, commonly known to the florist's trade: and the device of the applicant is one of practically universal range in relation to the ordinary sizes of flowerpots. The saucer B is not limited to any peculiar conformation, or material, but in the drawings I show such a saucer constructed of basic metal form having a flange or lip 8

formed on the side wall 7. In my preferable form I provide holes 9 penetrating the lip 8 at diametrically opposite points. I speak of that portion of the device, which is intended to receive and retain moisture for feeding the soil and plant in the pot, a saucer as seeming to be the best word for what is shown and intended: this saucer may be made of pottery material, metal, or some conveniently adaptable material suitable for the purpose and adapted to hold liquid for supplying the contents of the pot. The handle device is constructed of a single piece of resilient wire 10, having a bow portion with the ends 11 of the wire bent at substantially right angles thereto: in the primary form I show the bended ends 11 turned parallel to each other, although they may be bent at 12 inwardly toward each other as shown in Fig. 2. The ends may be further bent to make a loop form. Assembled on the said wire 10, somewhat remote from the bent ends I provide strips of metal 13 having more or less width and bent at an angle; one side of each angular piece having a perforation 14 by means of which it is loosely mounted upon the wire 10. In the operation of this device I utilize the tension of the bow in combination with the parts described to lock the handle to the saucer and firmly lock the pot to the saucer and the handle. In assembling the device the bent ends of the handle are inserted in the holes in the saucer with the handle lying substantially flat in the plane of the saucer. As the handle 10 is raised to an upright position the bent ends 11 pass under the lip 8 of the saucer B and stand in a position substantially as shown in Fig. 1; then the angular members 13 are slipped over the ledge of the pot by pressing a side of the bow until each angular member 13 is tensionally connected with the ledge of the pot; when the loosely mounted angular members are brought down to a relation where they hook over the edge of the pot the tensional strain of the bow member 10 acting upon the loosely mounted members 13 as a fulcrum and the lip 8 of the saucer as a point of power delivery the whole device is locked into a fixed relation for commercial purposes. It can be

as readily demounted by forcing one side of the bow 10 manually, as in mounting same, and raising one of the angular sliding members 13; the release of one affords an easy release of the other whence the pot can be removed, or even the three members conveniently separated.

A modified form may consist in a pair of trunnions, one extending out from either side of the saucer, in diametrically opposed relation; the ends of the wire being formed into a substantial loop or eyelet adapted to pass over the trunnions; there being provided indentations or recesses 9' on diametrically opposite portions of the liquid vessel ledge into which the wire portion is inserted to give fixed position to the saucer member; the handle being locked as before specified to the saucer and the pot by means of the angular 20 slidably mounted members 13.

I do not limit myself in the specification except in so far as I am limited by the scope of my claims.

I claim:

25 1. In combination a flowerpot, a saucer, a resiliently actuated handle and locking clips resiliently joining the flowerpot, saucer and handle.

30 2. The combination with a flowerpot and a saucer of a tensionally actuated handle comprising a resilient bow and adjustable clips adapted to mountably associate the said flowerpot in the said saucer and hold the handle, the pot and the saucer intact.

35 3. In combination a flowerpot, a saucer operatively associated with the flowerpot, a handle comprising a resilient bow portion and a means to lockingly associate the flowerpot, the handle, and the saucer in a unitary relation, locking the members together by the coaction of the resilient bow and its locking portions in association with the flowerpot and saucer.

45 4. The combination of a flowerpot, a saucer having a flanged edge or lip, retaining means on the lip of the saucer, a resilient wire handle comprising a bow portion with its ends terminating in bent portions, the said bent portions adapted to be attachingly associated with the lip of the saucer, members slidably mounted upon the resilient wire handle portion having means to tensionally lock in combination the flowerpot, the saucer and the handle.

55 5. A flowerpot combination comprising a flowerpot, a saucer having a ledge associated therewith, a handle consisting of a resilient wire with a bow portion associating the said flowerpot and the said saucer, means slidably mounted upon the wire portion adapted to contact with the ledge and a wall of the pot to demountably and resiliently associate the said members.

60 6. In combination a flowerpot, a saucer, a resiliently actuated bow member having pri-

mary anchorage in the saucer, slidably mounted anchoring members adapted to be brought into anchoring relation on the ledge and wall of the pot, the resiliency in the bow member coacting with the slidably mounted anchoring members and the saucer whereby to lockingly hold the combination as a unit.

65 7. A device for the purpose described comprising a resilient wire bent in the form of a bow having its terminals shaped to be attachingly associated with a vessel for retaining liquid, a vessel for retaining liquid, means adjustably mounted upon the bow portion adapted to be brought into contact with the ledge of a flowerpot and tensionally lock 80 the flowerpot and the bow member and the vessel for retaining liquid.

8. The combination of a flowerpot, a saucer associated with the said flowerpot, a resilient bow member comprising therein terminal 85 grips adapted to engage the rim of the saucer at diametrically opposite points, each leg of the bow member having somewhat distant the end a loosely mounted clip adapted to be brought to a position over the ledge of the 90 pot and coact with the resiliency in the bow member to lock the pot, the saucer and the bow member in a fixed relation.

9. An article of manufacture for the purposes described comprising a resilient handle member associated with a flowerpot and a saucer for the flowerpot, means on the saucer for retaining the ends of the bow member, means on the bow member for adjustingly associating the bow member to the flange 100 portion of the pot, the said means on the bow member co-operating with the bow portion and the saucer to hold the parts substantially in locking unitary relation.

Signed at Chicago, Illinois, May 26th, 1928.
